CLAIM

I claim the ornamental design for an alien drinking container, as shown and described.

DESCRIPTION

FIG. 1 is a front elevational view of an alien drinking container showing my new design;

FIG. 2 is a rear elevational view thereof;

FIG. 3 is a right side elevational view thereof;

FIG. 4 is a left side elevational view thereof;

FIG. 5 is a top view thereof; and,

FIG. 6 is a bottom view thereof.

The broken lines in each Figure depicting a cap, straw and/or engagement thread or ring for the cap are for illustrative purposes only and form no part of the claimed design.
